UNITED STATES PATENT OFFICE.

EARL A. PARKER AND CLAUDE W. MASSINGHAM, OF POPLAR BLUFF, MISSOURI.

FLYING MACHINE.

Application filed April 14, 1924. Serial No. 706,585.

To all whom it may concern:

Be it known that we, EARL A. PARKER and CLAUDE W. MASSINGHAM, citizens of the United States of America, residing at 5 Poplar Bluff, in the county of Butler and State of Missouri, have invented certain new and useful Improvements in Flying Machines; and we do hereby declare that the following is a full, clear, concise, and exact 10 description of the invention, such as will enable others skilled in the art to which it appertains to make and use the same.

This invention relates to improvements in flying machines of the lighter than air 15 type, having for an object to provide a dirigible and propelled airship having the load sustaining means or body thereof connected to the gondola or carriage in such a manner as to permit of relative uninterrupted 20 parallel movement therebetween, hence, permitting the craft so constructed, to be especially stable and efficient in flight under abnormal conditions, such as during storms and similar disturbances; it being at 25 all times possible to cause the craft to face the wind and thus secure thereto, its full power of propulsion and control.

An equally important object of the invention is to provide a flying machine, the 30 sustaining means of which is so constructed that the center of buoyancy and of gravity will be in the same vertical plane, hence, permitting the machine to constantly retain its full equilibrium.

It is also an object of the invention to 35 provide a flying machine with a novelly constructed and shaped sustaining beam or body, the same being circular in shape and formed with angular bow portions, thereby 40 affording superior qualities for the combating of wind friction and air resistance, together with the ability to ascend or descend when desired and under full control.

Other objects of the invention will be in 45 part obvious and in part pointed out hereinafter.

In order that the invention and its mode 50 of operation may be readily understood by persons skilled in the art, we have in the accompanying 55 illustrative drawings, and in the detailed following description based thereupon, set out one possible embodiment of the same.

In these drawings:

Figure 1 is a side elevation of the improved machine;

Figure 2 is a top plan view having portions thereof broken away, showing the shape or formation of the sustaining body;

Figure 3 is a vertical section through the 60 sustaining body; and,

Figure 4 is an enlarged fragmentary detail, partly in section, showing the swivel connection between the sustaining body and the machine gondola or carriage.

Having more particular reference to the drawings, in connection with which like characters of reference will designate corresponding parts, the improved flying machine may be stated to comprise a sustaining body 1, a gondola or carriage 2, and a swivel connection 3, such connection, obviously, serving to support the gondola 2 with respect to the sustaining body 1 and to permit of uninterrupted relative parallel 75 movement as between the two.

The sustaining body 1, being referred to in detail, may be stated to comprise a skeleton or superstructure comprehending concentrically arranged circular braces or trusses 4, of which there are two, as shown in the Figure 3. Radially disposed bars 5 are interconnected with these circular braces 4 and as will be noted, are so arranged as to provide a circular frame, the opposite sides thereof, that is, the upper and lower sides of which, are tapered outwardly, as is clearly shown in the Figure 3. Vertically disposed trusses 6 are positioned between the 80 opposite sides of the bars 5 at certain distances throughout their lengths and by reason of their connection with the adjacent portions of such bars will serve to effectually brace the same and likewise, to afford compartments for the various buoyant elements of the sustaining body to be presently described. In this connection, it will be noted that the marginal or bow portion of the sustaining body 1 is angled, and by 85 reason of this, it will be understood that the sustaining body will be given such superior qualities as will enable the same to 90 successfully combat wind friction and air resistance.

Fixedly connected to the lower side and central portion of the superstructure of the sustaining body 1 are a plurality of radially disposed supporting rods generally indicated by the numeral 7, the lower ends of which are passed through the flanged upper portion of a swivel connecting ring indicated in its entirety by the numeral 8. 105

This swivel connecting ring 8, as will be noted upon reference to the Figure 4, comprises a circular tubular-like body portion having a slot formed in the lower part thereof through which hanger brackets 9, connected to rollers 10 travelling within the circular tubular body may pass. A circular band 11 is fixedly connected to the lower ends of these hanger brackets as indicated at 12. Thus, it will be understood that by reason of the connection of the circular band 11 to the rollers 10, rotary movement as between said band 11 and the ring 8 will be permitted. Incidentally, it should be here noted that the swivel ring 8 is rigidly supported with respect to the sustaining body 1 through the medium of the various supporting rods 7.

Arranged within the central compartment 20 of the sustaining body superstructure, such compartment being afforded by the innermost vertical trusses 6, is a spherical gas-inflated bag 13, the upper and lower portions of which pass through the circular braces 4. Encompassing this spherical gas-inflated bag 13, but spaced therefrom, is an inner gas-inflated tube 14, the same being arranged in that compartment provided as between the innermost vertical truss or trusses and those trusses outwardly of but adjacent to the same. Yet another and outer gas-inflated tube 15 is arranged within the superstructure of the sustaining body 1 between another of the compartments 35 afforded by the arrangement of others of the vertical trusses 6, this latter gas-inflated tube, as will be noted, being spaced from the inner gas-inflated tube 14. To secure or support the gas-inflated bag 13 and the gas-inflated tubes 14 and 15 in suspended positions within the superstructure of the sustaining body 1, ropes or suitable forms of cables, generally indicated herein by the numeral 16, are passed about or wrapped over the bag 13, then crossed over the superstructure bars 5 and the trusses 6 and engaged about the inner gas-inflated bag 14 and then over portions of the superstructure bars 5 and others of the trusses 6, whereupon the ropes or cables are passed about the outer gas-inflated bag 15. The free or remaining ends of these ropes or cables are then arranged in criss-crossed relationship as indicated by the numeral 17 and secured to adjacent portions of the tapered marginal parts of the sustaining body superstructure, as clearly indicated in the Figure 3. In this way, it will be understood that the inflatable bodies within the sustaining body 1 will be immovably secured in their suspended positions with respect to their particular compartment within the superstructure of such sustaining body and in consequence, damage thereto, caused by constant rubbing or friction will be avoided and

likewise, the stability of the sustaining body brought about by positive positioning of the buoyant bodies therein will be ensured.

The superstructure of the sustaining body 1 with arrangement of the lighter than air bodies 13, 14 and 15 therein in the manner hereinbefore described, is adapted to be enveloped in a covering of suitable waterproof fabric or other material indicated by the numeral 18, such material, of course, being stretched taut over the superstructure of the sustaining body and having its adjacent portions joined by stitching, lacing, or other suitable means, common in the art.

The gondola or carriage 2 of the machine is adapted to be connected by hanger rods or similar devices 19 to the circular band or ring 11 and when so positioned, it will be understood that the same will be supported in substantial parallelism to the sustaining body 1. The gondola is provided with suitable motive means for driving the rotatable propeller 20 at the desired velocity, while the usual rudder or other steering apparatus 21 is provided upon the rearward or other desired portions of such gondola. Also, landing gearing 22 may be and preferably is provided the gondola for obvious purposes.

From the foregoing, it will be seen that we have provided a lighter than air flying machine of the dirigible and propelled type which by reason of its peculiar construction and formation of the sustaining body thereof will be permitted to successfully encounter and withstand heavy wind friction and air resistance. Because of the connection of the gondola 2 through the swivel 3 to the sustaining body 1, it will be also seen that the center of buoyancy and the center of gravity of the flying machine will be arranged in the same vertical plane, hence, lending materially to the stability of the machine as well as to its lifting and flying efficiency. Furthermore, because of the ability of the gondola 2 to move in an interrupted path of parallel travel with respect to the sustaining body 1, it will be understood that the propeller 20 thereof may, at all times, be brought head-on into engagement with wind friction or air resistance, whereas the propelling apparatus 21 of such gondola may be also advantageously positioned in order that the craft may be caused to carry on effectual flight through abnormal air conditions.

Manifestly, the construction shown is capable of considerable modification, and such modification as is within the scope of our claims, we consider within the spirit of our invention.

We claim:—

1. A flying machine comprising a lighter than air sustaining body consisting of a

superstructure having the upper and lower surfaces thereof tapered, gas inflated bodies retained in spaced relation within said superstructure, a carriage, a circular swivel ring fixedly connected to the under side and central portion of the superstructure, a circular band, rollers fixedly connected in spaced relation to said band and movably received in the circular ring, and means for effecting connection between said carriage and said band.

2. A flying machine comprising a lighter than air sustaining body consisting of a superstructure having the upper and lower surfaces thereof tapered, gas inflated bodies retained in spaced relation within said superstructure, one of said gas inflated bodies being spherical in shape and the others of said bodies being circular in shape and arranged concentrically with respect to said spherical body, a carriage, and means for rotatably connecting and supporting said carriage on said superstructure.

3. A flying machine comprising a sustaining body including a superstructure circular in shape and having its upper and lower surfaces tapered outwardly, a spherical gas-inflated body arranged within and centrally of said superstructure, a pair of concentrically arranged gas-inflated tubes within the superstructure and encompassing said spherical body, means for suspending said

spherical body and tubes within the superstructure and in spaced relation, a carriage, and means connected to the under side of the superstructure and arranged centrally of the same for swivelly connecting said carriage to the sustaining body and permitting of uninterrupted parallel movement therebetween.

4. A flying machine comprising a lighter than air sustaining body including a superstructure consisting of bars and struts arranged to render the same circular in shape and to have its upper and lower sides tapered outwardly, a spherical gas-inflated bag arranged within and centrally of said superstructure, gas-inflated tubes arranged concentrically with respect to each other within the superstructure and encompassing said gas-inflated bag, means for supporting said bag and tubes in suspended and spaced positions within the superstructure an envelope enclosing said superstructure, a carriage, a circular swivel ring fixedly connected to the under side and central portion of the superstructure, a circular band movably connected to said circular ring, and means for effecting connection between the carriage and said circular band.

In witness whereof we have hereunto set our hands.

EARL A PARKER.

CLAUDE W. MASSINGHAM.
